[57] **ABSTRACT**

Apparatus for manually operating plates provided with apertures such as telephone dials and the like, comprising two parts, one of which is provided with a handle and the other one being substantially conical, said two parts being interconnected via coupling means such that the conical part is movable relative to the first-mentioned part.

FIG.1

FIG. 2

FIG. 3

FIG. 4

FIG. 5

APPARATUS FOR MANUALLY OPERATING PLATES OR DISCS PROVIDED WITH APERTURES

This invention relates to an apparatus for manually operating plates or discs provided with apertures, in particular for rotating dials of telephone apparatuses.

A dial of a telephone apparatus is supposed to be moved with a finger which, however, in practice often is not done. For this purpose one often uses the end of a ball point pen or of a pencil. This entails the drawback of damage done the dial and, moreover, one's hand is forced to make considerable movements.

This is accomplished with the apparatus according to the invention in that it comprises two parts one of which is provided with a handle or is adapted to be secured to a handle and the other one is substantially conical, said two parts being interconnected via a coupling such that the conical part is rotatable relative to the first-mentioned part.

A preferred embodiment of the apparatus according to the invention is characterized in that the conical part is, moreover, adapted to be tilted relative to the part provided with a handle or adapted to be secured to a handle. Consequently the conical part which is destined to engage with the apertures of the plates or discs provided with apertures is capable of performing movements in every direction.

A simple apparatus which is easily manufactured may be obtained if the coupling consists of a ball which is fixedly connected to one of the two parts or is integral therewith, said ball being located in a correspondingly shaped accommodation cavity in the other one of said two parts. If the substantially conical part consists of somewhat elastic material, for example synthetic material, rubber or similar material, the ball may be easily pressed into the cavity provided in this part. If the material of the part comprising the accommodation cavity is less elastic, it is possible to provide around said accommodation cavity an annular groove in the part in question.

According to the invention the part coupled with the substantially conical part may have a broadened upper surface which serves as an abutment for the tilting movement of the conical part. Said broadened upper surface is preferably convex.

It is of advantage to have a writing implement, for example a ball point pen or pencil, serve as a handle of the apparatus according to the invention so that when writing one always has the apparatus at one's disposal. According to the invention the part adapted to be secured to a handle may be shaped as a cup for protecting sharp and/or vulnerable points.

The invention will be further explained below with reference to the drawings showing by way of example two embodiments of the apparatus according to the invention.

The drawings show in:

FIG. 1 a side view of a conical part of the first embodiment provided with a ball;

FIG. 2 a side view partially in longitudinal section of the part having an accommodation cavity for the ball of the conical part according to FIG. 1;

FIG. 3 the assembled apparatus partly in side view and partly in longitudinal section;

FIG. 4 a section through a conical part having an accommodation cavity;

FIG. 5 the part having a ball which is shaped to cooperate with the conical part according to FIG. 4.

The apparatus shown in FIGS. 1 to 3 comprises two parts, namely a substantially conical part 1 having a flattened or rounded top portion 2 and a flat base 3 provided with a ball 4, and a part 5 co-operating with said part 1. Part 5 comprises an accommodation cavity for the ball 4 of part 1. Around said accommodation cavity 6 there is provided an annular groove 7. As is apparent from FIG. 2 the upper surface 8 of the broadened upper portion 9 of part 5 is convex.

As is apparent from FIG. 3 both parts 1 and 5 are coupled with the aid of the ball 4 such that the base surface 3 extends at a small distance from the upper surface 8 of the broadened upper portion 9 of part 5. Consequently part 1 is adapted to rotate as well as tilt relative to the part 5. The upper surface 8 thereby serves an abutment to limit the tilting movement.

The embodiment shown in FIG. 4 and 5 differs from the one according to FIGS. 1 to 3 only by the fact that in part 1' an accommodation cavity 6' and an annular groove 7' are provided, the part 5' being provided with a ball 4'.

Parts 1, 1' and 5, 5' may be manufactured from synthetic materials, rubber or similar material. In this way the apparatus is prevented from damaging the disc or plate which is operated while the ball may easily be inserted into the accommodation cavity so that if the material of one or both parts is sufficiently elastic, the groove 7 or 7' respectively is superfluous. If a less elastic material is used the groove 7 or 7' respectively still renders it possible to press the ball 4 or 4' respectively nevertheless into the accommodation cavity 6 or 6' respectively. Part 1 or 1' respectively is embodied such that its base has a larger diameter than the one of the apertures in the disc or plate to be operated. In this way the upper portion 2 of part 1 does not come into contact with parts or surfaces located under the operated disc or plate.

In consequence of the fact that the conical part 1 or 1' respectively is adapted to rotate or tilt the advantage is obtained that when part 1 is inserted into an aperture of a disc or plate, said part remains immobile in said aperture during rotation or movement of the dial or plate thus preventing damage. Application of the apparatus causes the movements of the hand and the arm to be considerably smaller so that fatigue symptoms will be reduced.

It is obvious that the invention is not restricted to the embodiments described above and shown by way of example in the drawings, but that these may be modified in many ways without departing from the scope of the invention. Any suitable coupling may be used as a coupling of the two parts. The base of parts 1, or 1' respectively and the upper surface of parts 5 or 5' respectively may be formed in any suitable way. In the embodiment shown part 5 or 5' respectively is given the shape of a pin which for example may be inserted into the upper end of a ball point pen. It is obvious that this part can also be shaped as a cup into which the upper end of a ball point pen, pencil or some other writing or drawing implement can be inserted. Said cup may then also serve to protect the point of the writing or drawing implement when not in use.

I claim:

1. An apparatus for manually operating plates with apertures such as a telephone dial comprising two parts, the first part being provided with a handle and

the second part being substantially conical with a base which faces the end of the first part, said two parts being interconnected by a ball coupling with the conical part rotatable relative to the first part and also being tiltable relative to the first part with the first part having a broadened upper surface serving as an abutment for the tilting movement.

2. An apparatus for manually operating plates with apertures such as a telephone dial comprising two parts, the first part being provided with a handle and the second part being substantially conical with a base which faces the end of the first part, said two parts being interconnected by a ball coupling with the conical part rotatable relative to the first part and also being tiltable relative to the first part with an annular groove 15

around the cavity which accomodates the ball.

3. Apparatus for manually operating plates provided with apertures such as dials of telephone apparatuses and the like, said apparatus comprising two parts one of which being provided with means for fixing it on a handle consisting of a writing implement, the other part being substantially conical, said two parts being interconnected via a coupling consisting of a ball on one of said parts and an accommodation cavity for said ball in the other of said parts, an annular groove being provided around said accommodation cavity, the two parts being made in such a way that the conical part is adapted to be tilted with regard to the other part.
